BY
Stuart G. Barnes
ATTORNEY.

UNITED STATES PATENT OFFICE.

HERBERT R. BLISS, OF NIAGARA FALLS, NEW YORK.

SHIPPING CASE.

Application filed April 16, 1923. Serial No. 632,556.

To all whom it may concern:

Be it known that I, HERBERT R. BLISS, a citizen of the United States, residing at Niagara Falls, in the county of Niagara and

5 State of New York, have invented certain new and useful Improvements in Shipping Cases, of which the following is a specification.

This invention relates to a method for 10 sealing fiber shipping cases; it has especial application to fiber shipping cases intended to have a butt meeting of the edges of the flaps.

In my method of sealing it is possible 15 to secure this by arrangement of the edges of the outer flaps without using relatively long, overlapping flaps on the side walls resulting in a large wastage of material. So far as I am aware, no one has heretofore 20 sealed butt meeting flaps without using inner flaps that are substantially as wide as the outer flaps and either meet under the outer flaps or approximate a meeting condition.

25 In my co-pending application No. 501,620, I have described and claimed a method of sealing fiber shipping cases with what I term an H arrangement of stitches. The arrangement in that application as shown is 30 intended primarily for over-lapping flaps; it is the object of the present invention to afford an improvement over the method shown in application No. 501,620 so as to permit the sealing of the flaps by a general 35 H arrangement of stitches although the flaps do not overlap.

The overlapping flaps form a strong sealing arrangement but for some purposes are 40 objectionable as they provide a slight hump in the center of the case due to one flap overlying the other. In some classes of course, especially where conveyors are used, and for piling in warehouses and resealing, it is desirable to have a box which has an 45 absolutely flush face. This is afforded by the butt flaps sealing that is already explained, but so far as I know, this butt flap sealing has only been effected where relatively long flaps on the end walls have been 50 utilized resulting in a vary large and unnecessary wastage of material.

Referring to the drawings:

Fig. 1 is a perspective view of a shipping case sealed by my improved method.

Fig. 2 is a perspective view of the same before sealing.

Fig. 3 is a plan view showing how the initial stitches are taken, the order in which the stitches are taken being shown by the numerals.

Fig. 4 is a similar plan view showing the second step in the method.

Fig. 5 is a plan view showing the third step in the method.

Figs. 6, 7 and 8 are sections on the lines 65 6—6 of Fig. 3 and 7—7 of Fig. 4, and 8—8 of Fig. 4, respectively.

Figs. 9, 10, and 11 show plan views of an alternative method of stitching.

Fig. 12 and Fig. 13 are plan views of 70 the main blank and the end blank on a small scale.

The main body blank is shown in Fig. 12, and comprises a bottom wall *a*, side walls *b*, and cover wings *c*. The cover wings are 75 of just sufficient width to meet at the center of the top as shown in Fig. 1. The end blank is shown in plan view in Fig. 13 and comprises a main body *d* and sealing flaps *e*. Side flaps *f* and bottom flaps *g*. The 80 side and bottom flaps are adapted to fit around the side walls *b* and the bottom wall *a* of the main body blank as shown in Figs. 1 and 2, and to be stitched thereto by wire stitches *h*. This forms an improved body 85 construction which is no part of the present invention and which has been claimed in my co-pending application No. 514,788.

The substance of my present invention resides in sealing a shipping case which has 90 relatively narrow sealing flaps at the ends and abutting outer flaps; it is immaterial how the body construction bearing these abutting cover wings and sealing flaps is constructed or arranged.

The sealing flaps *e* are turned in as shown in Fig. 3, the stitches 1, 2 and 3 are then taken with the aid of an anvil *J* called a blade anvil by reason of its thinness. Of course, it will be understood that a suitable 100 stitching head of conventional type is employed with this blade anvil or for that matter conceivably the stitches could be driven in by hand so far as the broad conception of my process is concerned.

The operator then takes a strip of fiber board, which I will call a "coupling strip", and later on a "concealed coupling strip"; this coupling strip *k* is held by the operator while stitches 4, 5, 6, 7, 8 and 9 are taken. The operator can then take stitches 10, 11 110 and 12, which secures the left hand cover

wing *c* to the sealing flap *e*. This completes the first step of the method which really involves three sub-steps but is called the first step because the general position of the 5 box with respect to the anvil is not altered. It will be noticed that in taking this step the right hand cover wing is turned back as shown in Fig. 3.

To take the second step of the method the 10 cover wing *c* that has been turned back is turned over so as to overlap the unstitched side of the coupling strip *k*. The anvil *j* is then inserted over the sealing flap *e* and under the coupling strip *k* and the right 15 hand cover wing *c*; the stitches 13, 14 and 15 may then be taken and following this, stitches 16, 17, 18, 19 and 20. It will be seen, however, that between stitches 19 and 20 on the cover wing and the sealing flap *e* sufficient space is left to insert the anvil as 20 shown in Fig. 5.

This permits the third step to be taken wherein the anvil is inserted in the opposite end over the sealing flap and under the 25 opposite sealing flap and the right hand cover wing enabling stitches 21, 22 and 23 to be taken.

In Figs. 9, 10 and 11, the same general method is involved except that in step two, 30 the stitching along the coupling strip begins at the center instead of at the extreme end while in step three the stitching also begins at the center and goes toward the opposite end; it is the same general method and the 35 same general steps are taken.

It will be obvious that the stitches taken do not have to be taken in the order set down by the numerals. The broad novelty of the method resides in the using of a coupling strip and taking the general arrangement of stitches indicated in the specification and shown in the drawings. In its more specific embodiment, this embodies the use of a concealed coupling strip, inside 40 abutting flaps and an **H** arrangement of 45 stitches when viewed in plan, preferably with the center bar of the **H** in the form of a double bar.

What I claim is:

50. 1. A method of sealing shipping cases of fiber board or equivalent material, in which a pair of substantially abutting outer cover wings are provided, and a pair of relatively narrow sealing flaps at the ends in widely 55 spaced relation underlying the cover wings, comprising the fastening of a coupling strip to both outer abutting flaps and the fastening of the outer abutting flaps at the ends to the underlying sealing flaps by metallic 60 fasteners.

2. A method for sealing shipping cases of fiber board or equivalent material, in which a pair of substantially abutting outer cover wings are provided, and a pair of relatively 65 narrow sealing flaps at the ends in widely

spaced relation underlying the cover wings, comprising the fastening of a coupling strip to the underside of both cover wings at their abutting edges by metallic fasteners, and the fastening of the ends of the overlying cover 70 wings to the relatively narrow sealing flaps.

3. A method for sealing shipping cases of fiber board or equivalent material, in which a pair of substantially abutting outer cover wings are provided, and a pair of relatively narrow sealing flaps at the ends in widely 75 spaced relation underlying the cover wings, comprising the turning in of the sealing flaps at the ends of the case, the turning in of one cover wing over the sealing flaps, the 80 securing the ends of such cover wing to the sealing flaps underlying, the securing of a coupling strip to the underside of the overlying cover wing at its free edge so as to project therefrom, then the turning in of the 85 other cover wing and securing the same to the underlying coupling strip, and also the underlying sealing flaps at the ends of the cover wing.

4. A method for sealing shipping cases 90 of fiber board or equivalent material, in which a pair of substantially abutting outer cover wings are provided, and a pair of relatively narrow sealing flaps at the ends in widely 95 spaced relation underlying the cover wings, comprising the turning in of the narrow sealing flaps at the ends, the turning in of one cover wing to overlie the sealing flaps, the stitching of the end of 100 said cover wing to the underlying sealing flaps, the stitching of a coupling strip to the free edge of the cover wing in such a way as to cause a portion of the coupling strip to project beyond the free edge of the wing, the turning in of the other cover wing to 105 overlap the projecting portion of the coupling strip, and the stitching of said cover wing to the said coupling strip and to the sealing flaps at its ends.

5. A method for sealing shipping cases 110 of fiber board or equivalent material, in which a pair of substantially abutting outer cover wings are provided, and a pair of relatively narrow sealing flaps at the ends in 115 widely spaced relation underlying the cover wings, comprising the turning in of the narrow sealing flaps at the ends, the turning in of one cover wing over such sealing flaps, the placing of the blade anvil under the sealing flaps and the cover wing and driving metallic fasteners through both ends of the cover wing and the two sealing flaps, and also placing a coupling strip under the 120 free edge of the cover wing with a portion of the coupling strip projecting beyond such free edge and the driving of metallic fasteners through the cover wings and such coupling strip and clinching them with such blade anvil, the removing of the blade anvil and the turning in of the other cover 125 130

wing over the sealing flaps and the coupling strip, the insertion of the blade anvil in at one end over one sealing flap and under the cover wing last mentioned, and the coupling strip, the driving metallic fasteners through the cover wing and the coupling strip and clinching them on the anvil, the driving of metallic fasteners through the cover wing and the opposite sealing flap but leaving an unattached space for the withdrawal of the anvil, the insertion of the anvil through the opposite end of the case through the space which has been left, and the stitching of the cover wing to the sealing flap at the opposite end.

6. A method for sealing shipping cases of fiber board or equivalent material, in which a pair of substantially abutting outer cover wings are provided, and a pair of relatively narrow sealing flaps at the ends in widely spaced relation underlying the cover wings, comprising the stitching of the ends of the cover wings to the underlying

sealing flaps and stitching the abutting edges of the cover wings to an underlying concealed coupling strip.

7. A method for sealing shipping cases of fiber board or equivalent material, in which a pair of substantially abutting outer cover wings are provided, and a pair of relatively narrow sealing flaps at the ends in widely spaced relation underlying the cover wings, comprising the turning in of the narrow sealing flaps at the ends, then turning in the cover wings one at a time and in such operation wire stitching the cover wings to the end flaps and to an underlying concealed coupling strip extending from the underlying sealing flap at one end to the other underlying sealing flap at the other end along and under the meeting edges of the cover wings.

In testimony whereof he has affixed his signature.

HERBERT R. BLISS.
